UNITED STATES PATENT OFFICE.

FRANK BOULTON ASPINALL, OF BLACKHEATH, LONDON, ENGLAND.

PRODUCTION OF MOTIVE POWER.

1,128,834.

Specification of Letters Patent. Patented Feb. 16, 1915.

Application filed October 11, 1912. Serial No. 725,243.

To all whom it may concern:

Be it known that I, FRANK BOULTON ASPINALL, a subject of the King of Great Britain, and resident of 8 Wemyss road, Blackheath, London, England, engineer, have invented new and useful Improvements in the Production of Motive Power, of which the following is a specification.

The principal object of this invention is to reduce the enormous heat losses which at present take place even in the best steam practice but it is also designed to reduce the heat losses in other heat carriers such as air used in motive power engines. To attain this end, I carry out a cycle of operations which enables the steam or other heat carrier to be utilized to better advantage in the engine and also permits the recovery and use over and over again of the greater part 20 of the heat which leaves the engine in the exhaust.

In the accompanying drawing, Figure 1 is the card of the cycle used in a steam engine in present day practice. Fig. 2 is the 25 card of the cycle embodying my improvements. Fig. 3 is the card of the "Carnot" cycle. Fig. 4 is the card of the compression of the exhaust steam used in accordance with my improved cycle. Fig. 5 is a 30 diagram showing the cycle of operations embodied in my invention, and Fig. 6 is a diagram of the plant which I propose to employ.

In the cycle used in a steam engine in 35 present practice, if all the work is done in one cylinder as shown diagrammatically in Fig. 1 of the accompanying sheet of diagrams steam is admitted from a to b cut off at b , expanded from b to c , exhausted from 40 c to d and the remainder compressed from d to a to fill in the clearances. But, in this method of working, enormous variations of temperature take place in the steam during 45 its passage through the cylinder and consequently in the temperature of the metal which comes in contact with the steam. The fact of the metal being a conductor of heat still further complicates matters. This and the inevitable clearances tend to reduce the 50 work done, below what is theoretically possible. In the best modern practice however, matters are improved to a certain extent by the steam being superheated when received by the engine. It is evident that exactly 55 the same work would be done if the steam were admitted from e to f (see Fig. 2)

dropped in pressure from f to g when the exhaust opens, exhausted from g to h and compressed from h to e provided that the effective mean pressures were in each case 60 the same and, as the temperature of the steam would not vary to the same extent inside the cylinder the metal with which the steam comes in contact would also not vary to the same extent, thus reducing the metal's 65 ill effect. Again, as the pressure at e is less than at a , less weight of steam is required to fill the clearances. I therefore propose to produce steam at the volume which steam containing no water and no superheat would 70 have at the pressure g , but superheated to such a temperature that its pressure is nearly equal, equal, or more than equal to the pressure at e depending on the superheat, the steam being then at a large volume per unit 75 of weight. Or in other words I produce steam at a certain pressure and then, by superheating it, increase its volume till the volume is equal to the volume of steam containing no water and no superheat at the 80 pressure g , the pressure remaining constant so that the steam occupies a large volume per unit of weight. The steam thus produced I admit for the full stroke, or approximately so, at the initial pressure. It 85 will be noticed, however, that if the steam or other motive fluid is in the condition stated when admitted to the engine that it is possible, provided it is considered desirable or expedient to do so, to expand the 90 steam while work is being done, either by cutting off or gradually throttling throughout the stroke, without altering the fact that the steam or other working fluid is always at such a large volume per unit of weight 95 when doing work that the pressure necessary to do the work is principally, if not wholly, due to the superheat or excess of heat present.

Now it is obvious that both with the ordinary method and also with my own so far as it has been herein described a large amount of heat is wasted which is in the exhaust, even although some is recovered by an exhaust steam feed water heater or 105 from the hot well. I am aware that heat is recovered from the exhaust in what is known as the "Carnot cycle" as shown in Fig. 3, for steam is received from k to l expanded from l to m , condensed from m to 110 the point n , that is until there is such a quantity of steam and water at n that when

the mixture is compressed to the pressure k there is all water present at the temperature of steam at the pressure k , this water then being turned again into steam. But, in 5 present day practice, practically, the same result is obtained by an economizer. Binary fluid engines have also been proposed to utilize heat in the exhaust. To recover heat from the exhaust, I proceed in a totally different way. As already described I admit steam for the full stroke from e to f , the steam being superheated to such an extent that if the superheat were removed, the pressure would not be that at e but that at g 10 so when the steam is exhausted from the engine, I abstract the superheat dropping the pressure to g . The steam is then, instead of being condensed, drawn into a compressor, compressed to the pressure e and returned 15 to the original steam space to be again superheated. The steam, after the superheat is removed is compressed, see Fig. 4 from o to p put into the original steam space from p to q , the clearance steam expander from q to r and fresh steam drawn into the compressor from r to o . The card off the engine cylinder as shown in Fig. 2 therefore represents more work than the card off the compressor cylinder as shown in Fig. 4. The difference 20 between the two cards less the frictional loss is therefore available for external work. The fact that the heat in the steam, after the removal of the superheat is returned 25 to the original steam space, reduces the amount of heat which has to be provided to superheat the steam to the desired temperature. The heat in the steam when it reaches the pressure at p will also be more 30 than when the steam is at the pressure at o , the amount depending upon the heat lost and gained during compression.

The work available for external use can be varied by altering the amount of superheat which is abstracted from the steam before it is compressed as this will vary the amount of work done in the engine cylinder by increasing or diminishing the back pressure and also by increasing or diminishing 45 the work absorbed in the compressor cylinder relatively to the work produced in the engine cylinder. By this method of governing, the temperature is always kept the same from e to f , but there are other methods of 50 governing, such as altering e and g and the admission temperature, etc. I mention this, because it is impossible to consider all the various purposes and conditions for which steam power is required and the relations of 55 capital economy to heat economy.

In the above description I have not dealt with any temperatures or pressures but in actual practice I should make the temperature at e as reasonably high as the conditions permit and if I were working con-

densing would make the pressure g as low as possible relatively to the pressure at e so that such a mean pressure is obtained as to secure a fair duty out of a given sized cylinder governing being done by throttling 70 and the steam being passed through a feed-water heater before it is condensed. When working differentially, however, that is on the difference between the work produced in the engine cylinder and the work absorbed in the compressor cylinder, I should also work at the highest reasonable temperature but vary e and g according to circumstances. Shortly, to get the heat economy, I circulate the heat which is in the steam after the necessary amount of superheat has been abstracted and then, by adding and abstracting further heat, produce external work. 80

In Fig. 5 a diagram is given showing the cycle of operations, the steam circulating 85 in the direction of the arrows. Steam is produced in the superheater z its temperature and pressure being ascertained by the gage y and thermometer x near the point where it enters the engine. Its temperature 90 and pressure are such that if the superheat were removed the steam would be at a much lower pressure. The steam then passes through the engine cylinder w giving a card as in Fig. 2. On admission to the cooler v 95 the superheat is abstracted thus reducing the pressure in the cooler below that of the pressure in the superheater. The steam next circulates to the point where it enters the compressor u its temperature and pressure being ascertained by the thermometer t and gage s at this point. It is then drawn into the compressor, compressed to the pressure in the superheater (see card Fig. 4) 100 and put into the superheater to be again superheated. The steam during its passage through the cooler is not condensed as it is always superheated, the amount of superheat which is in the steam when it enters the compressor depending upon the load on the engine. By suitable arrangements the weight of steam withdrawn from the cooler equals the weight of steam which enters the cooler, precautions also being taken against any excessive heat losses in the compressor 110 especially at top load. It will be noticed that steam is being exhausted into and removed from the cooler at the same time and steam is also entering and leaving the superheater at the same time, but the actual 115 steam leaving the superheater and cooler has entered the superheater and cooler some strokes previously, the number of strokes depending upon the relative volumes of the superheater, engine cylinder, cooler and compressor. A time interval is therefore 120 allowed for the steam to receive and lose superheat. The superheater volume is such that there is no considerable variation of pressure. When working with this cycle, 125 130

the external work does not depend upon the steam consumption as no steam is consumed, but upon the total heat which can be or may be added and abstracted during the circulation of the steam. The amount of the possible external work can therefore be increased or decreased by altering the total amount of heat which it is possible to add or abstract in a given time during the circulation of the steam.

In Fig. 5, if the maximum temperature in the superheater is a constant and the speed of the engine is constant making the volume of steam passing through the engine a constant, the weight of steam circulated in a given time can be increased or decreased by adding or abstracting steam from the superheater, and, as the weight of steam circulated varies, the heat, which can be added and abstracted, varies. Of course the pressures in the superheater and the cooler increase if steam be added but the difference between the two pressures also increases and likewise the pressure effective for external work. Thus, more external work can be done but at the expenditure of more heat. For instance, if steam at 4 lbs. and 50 lbs. pressure are superheated to 500° F. the increase of pressure will be more with the 50 lbs. steam because its density is more.

It is evident that if the pressure in the superheater is increased to such an extent that there is no superheat when the steam enters the engine cylinder, the engine will not work as the pressures on the two sides of the engine piston will be the same or, if the pressure in the superheater is too low, all the work produced will be absorbed in overcoming friction. The best pressure to have in the superheater depends upon the maximum temperature allowed in the superheater, the purpose and conditions which have to be met by the engine, and the constructional details of the plant. By circulating a reasonable weight of steam reasonably sized cylinders can be used to get the work without abnormal maximum temperatures in the superheater. This method of working may possibly be thought to approach more closely to that of a hot air engine, so it must not be confused with the proposals of Joule, Erickson, and Stirling because it is different in many essential respects, among others being the fact that my steam is circulated and the back pressure on the engine can be varied instead of being kept at atmospheric pressure.

In Fig. 6, as an illustration a diagram is given of a general arrangement for carrying out my purpose but, as previously pointed out, in actual practice, the arrangement may be modified to suit the conditions which have to be dealt with. 1 is a boiler which may be very small as it is only required for

starting up, for making good any loss of steam and for varying the pressure e if desired. As a matter of fact, if the superheater is used as a flash boiler the boiler 1 can be replaced by a feed tank. 2 is a valve which controls the admission of steam or water to the superheater. 3 is a valve which is kept closed at starting up to prevent condensation in the pipes, but is opened full bore when on load. 4 is the superheater; 5 the engine mainstop valve; 6 a valve which enables steam to be passed through the superheater to keep it cool if the engine is suddenly shut down and the dampers on the superheater are not sufficient to keep the superheater from being overheated. 7 and 8 are the thermometer and gage for ascertaining the temperature and the pressure of the steam on admission to the engine cylinder. 9 is the engine cylinder which has no expansion valve but a simple valve to give a card shaped like in Fig. 2. 10 is the exhaust pipe but if desired, the steam can be passed through a jacket on the engine cylinder after it is exhausted. 11 is the reheat or jacket to the steam on its way to the superheater after it has been compressed; 12 the point where the steam leaves the reheat; 13 a valve which can be opened to the atmosphere before putting the engine on load and for blowing off steam when shutting down. It can also be used, if necessary to adjust the pressure in the cooler. 14 is a valve blowing steam into the cooling water so as to warm up the cooling water and cooler before starting to the desired temperature. 15 and 15^a are valves for shutting off steam from cooler till it has been warmed up, so as to prevent water accumulating in the cooler due to condensation. 17 and 18 are the gage and thermometer for ascertaining the temperature and pressure of the steam on admission to the compressor cylinder. 19 is the compressor cylinder which gives a card shaped like in Fig. 4. 20 and 21 are the thermometer and gage for ascertaining the temperature and pressure of the steam on leaving the compressor, the chief use of which is to ascertain the steam's temperature and pressure so as to tell if everything is warmed up thoroughly. 22 is a valve to shut off steam from the pipe leading to the superheater when warming up; 23 a valve to allow steam to be blown into the atmosphere when warming up; 24 is a valve to adjust the amount of water supplied to the cooling tank; 25 a drain from the tank containing the cooling water to run off the hot water which water, if desired, can be passed through a jacket on the compressor cylinder to reduce the heat losses in the compressor. By suitable means the abstraction of heat by the cooler can be governed according to the load.

In the method of warming up described, the engine is turning around, but by having suitable by-passes at the engine and compressor cylinders, this could be done with the engine standing. These also could be used so as to keep everything warm if the engine is required to be constantly stopped and started. This arrangement also provides means for varying the pressures in the super-
 10 heater and cooler on load if desired. The cooling water may be used under pressure to get a higher temperature in the compressor jacket, if desired. The cooler may be air cooled. The cycle is the same when a carrier of heat other than steam is employed, minor differences only with different heat carriers being necessary.

In working according to my invention precautions should be taken to a greater extent than in an ordinary engine to prevent loss
 20 of heat by radiation or conduction.

What I claim and desire to secure by Letters Patent of the United States is:—

1. A method of producing motive power
 25 which comprises expanding working fluid to

a large volume by superheating it without altering its pressure, passing it through an engine in that condition, exhausting it while still superheated, abstracting the superheat, thus reducing the pressure, and compressing this reduced pressure steam to the original pressure ready for superheating again.

2. A method of producing motive power which comprises compressing working fluid to the desired pressure, expanding it to a large volume by the addition of heat, passing it through an engine in that condition, exhausting it while still heated, removing the heat without materially altering the volume and compressing it to the original volume ready for a fresh supply of heat substantially as described.

In testimony whereof I have signed my name to this specification in the presence of two subscribing witnesses.

FRANK BOULTON ASPINALL.
